UNITED STATES PATENT OFFICE.

VERNER T. STOCKTON, OF OKEMAH, OKLAHOMA.

CLEVIS.

Application filed December 2, 1921. Serial No. 519,445.

To all whom it may concern:

Be it known that I, VERNER T. STOCKTON, a citizen of the United States, residing at Okemah, in the county of Okfuskee and 5 State of Oklahoma, have invented certain new and useful Improvements in Clevises, of which the following is a specification.

This invention has reference to clevises and particularly to a locking device for the 10 clevis pin.

An object of the invention is to provide a clevis having a self locking clevis pin that will automatically bind itself against displacement, thereby avoiding the loss of a 15 pin while the clevis is in use.

An additional object is to provide an improved type of clevis in which the pin is automatically and tensionably locked securely in place although readily removable 20 when desired; the invention being applicable to clevises of various sorts.

Various other objects and advantages of the invention will become apparent during the continuance of the following description. 25

Figure 1 is a side elevation view of the clevis, partly in section disclosing the method of locking the pin.

Figure 2 is a top plan view thereof.

Figure 3 is a transverse cross section taken on line 3—3 of Figure 1, and,

Figure 4 is a detailed, in perspective, view of the locking pin.

The clevis, indicated in the drawings at 35 10, is preferably U-shaped and is tapered so that the arms widen out toward their free end. The clevis is thus strongest where the strain is heaviest.

Each arm is provided with an opening 40 11; the opening being in alignment to receive the shank 12 of the clevis pin. At the free end of one of the clevis arms and on the outer face thereof is a locking lip 13 having its under face inclined with respect to the face of the arm, as indicated at 45 14, thus providing a wedge-shaped opening into which the tongue 15 of the clevis pin is adapted to be inserted. Locking lip 13 may be an integral part of the clevis and

50 may be formed by bending back the outer free end of a clevis arm as indicated in Figure 1 of the drawing. This lip extends back to a point directly even with the edge of hole 11 as will be apparent from Figure

55 2. Formed in the lip-bearing arm of the clevis is an elongated cavity or depression

16 having sloping sides 17. Adapted for engagement with cavity 16 is the extension 18 carried by the head 19 of the clevis 10. As shown in detail in Figure 4, the head 60 of the pin is projected from opposite ends and provided with a wedge-shaped tongue 15 and the extension 18. The extension is provided with a smooth faced knob on its under side adapted to slide easily over the 65 sloping walls of the cavity 16 and to fit in the latter as shown in Figure 1. The head of the pin is weakened at a point intermediate the knobbed face of the extension and a tongued-end of the head, as indicated 70 at 20, to provide for a slight yielding movement of the extension.

When securing the pin to the clevis, the shank 12 is inserted through openings 11, the head of the pin being disposed at right angles to the clevis arm as indicated in dotted line in Figure 2. After the shank is engaged with both of the clevis arms, the head of the pin is swung around until wedge-tongue 15 with its inclined face engages under locking lip 13. At the same time, extensions 18 may be elevated slightly and against its own tension to clear the sides of the clevis arms so that when released, it will drop down into cavity 16. The extension is normally tensioned to exert a downward pull and hence it will fit snugly in the cavity of the clevis arm and hold the pin firmly in place. In order to release the pin, tongue 15 must be forced by some convenient 90 tool from under locking lip 13 until it is at right angles to the lip, the locking extension 18 riding easily and upwardly over the inclined walls of the cavity as the tongue is driven to its releasing position. It will thus 95 be seen that the tongue and extensions serve automatically to lock the pin to the clevis and to prevent casual displacement of the pin while the clevis is in use.

From the foregoing it is believed that the 100 advantages and novel features of the invention will be readily understood and therefore further detailed description is deemed unnecessary.

What is claimed is:—

1. A clevis having a pin opening and a depression on one side of the opening and provided with sloping walls, a locking lip integral with the clevis and on the opposite side of the pin opening, a clevis pin associated with said clevis, said pin having a shank penetrating the clevis between the de- 110

- pression and the locking lip and a tensionable head carried by the shank and extended on opposite sides thereof to provide a locking tongue engageable under the said locking lip and a spring extension engageable with the depression, said extension riding easily over the sloping walls of the cavity as the tongue is alternately swung into and out of engagement with the said locking lip.
10. 2. A U-shaped clevis, the arms of which have openings aligned, one of said arms having its free end extended and reversed to provide a locking lip having its terminal edge aligned with the edge of the opening and arranged at a slant to the arm to provide a wedge-shaped recess said arm also having a depression on the opposite side of the opening, a clevis pin having its shank insertable through the aligned openings of the arms and a head having opposite ends extended providing respectively a locking tongue engageable under the locking lip and an extension engageable in the depression, said head being weakened at a point between the tongue and extension to make the latter elastic.

3. A clevis comprising a U-shaped member tapered so that the arms widen out towards their respective free ends, and a clevis pin consisting of a shank and an integrally formed head thereon presenting an elongated smooth-faced tensionable knob on one side of the shank and a relatively stiff non-yielding tongue on the opposite side, the said shank of the pin being insertable through aligned openings in the arms of the clevis with the head of the pin initially disposed at right angles to the clevis arms, one of the said arms having the portion beyond the opening bent back to a point directly even with the edge of the opening to provide a locking lip and having the portion adjacent the opposite side of the opening formed with a cavity having sloping walls, the said lip and cavity of the said arm serving to respectively engage and seat the said tongue and knob portions of the said head when the latter is turned to rest longitudinally along the said arm.

In testimony whereof I affix my signature.

VERNER T. STOCKTON.
